UNITED STATES PATENT OFFICE.

EDWARD J. BROOKS, OF EAST ORANGE, NEW JERSEY, ASSIGNOR TO E. J. BROOKS & CO., OF NEW YORK, N. Y.

SEALING-PRESS.

SPECIFICATION forming part of Letters Patent No. 242,259, dated May 31, 1881.

Application filed March 10, 1881. (No model.)

To all whom it may concern:

Be it known that I, EDWARD J. BROOKS, a citizen of the United States, residing at East Orange, in the State of New Jersey, have invented a new and useful Improvement in Sealing-Presses, of which the following is a specification.

This invention relates to means for applying seals and tags or seals to railway-cars, baggage, packages of valuable merchandise, and the like, and for opening cars, &c., so sealed by cutting the sealing strips or wires.

It relates more particularly to the construction and use of a sealing-press for pressing or stamping sheet-metal seal-shackles in the peculiar manner described in my specification forming part of Letters Patent No. 236,539, dated January 11, 1881—to wit, so as to provide the same with raised retaining-projections in the form of numbers or distinguishing-marks, or in any preferred form to effectually prevent the withdrawal of their pressed or stamped ends through contracted threading-holes.

My present invention consists, first, in a novel combination of parts in a sealing-press, comprising a pair of pivoted-or sliding dies or die-jaws actuated by direct pressure in a central plane, simultaneously and with equal or substantially equal force, as required for pressing or stamping in the most effective manner each of the two protruding ends of my patented sheet-metal seal-shackle aforesaid, as combined with a tag or keeper separate from the sealing-strip, the same being also advantageously suited to the pressing or stamping of the "sealing-sleeves" described and claimed in my specification forming part of Letters Patent No. 235,668, dated December 21, 1880, and to the pressing of the soft-metal seal-disks of "lead-and-wire" seals, and to the union of the ends of sealing-strips by eyelet-punching and like means, as hereinafter set forth. In either case the said combination provides for pressing or stamping two metallic steel surfaces by independent die action at one and the same operation, and so as to insure sharpness of impression and uniformity of compression with economy of power.

This invention consists, secondly, in a novel

combination of dies in a sealing-press for pressing or stamping the threaded end or ends of a sheet-metal seal-shackle, the same being adapted to do the work at one operation, whether both ends or only one end of the shackle be pressed or stamped.

This invention consists, thirdly, in sealing-dies of peculiar construction, the same being adapted to form stiffened and thickened shoulders or offsets on the threaded end or ends of a sheet-metal seal-shackle to prevent the withdrawal of the pressed end or ends through a contracted threading-hole, as hereinafter set forth.

This invention consists, fourthly, in a pair of intaglio die-jaws, in combination with a cameo middle die for raising retaining-projections on the threaded end or ends of a sheet-metal seal-shackle, said construction of the respective dies serving to facilitate the insertion of the shackle ends between the dies; fifthly, in a pair of pivoted die-jaws united below their pivots by an opening spring common to both, as a feature of superior simplicity and efficiency; sixthly, in a shackle-cutter knife held in a dovetailed seat in the said head of the press by the said spring of the die-jaws, and adapted to co-operate with the shank of one of the pressing-levers, as hereinafter specified.

In the accompanying drawings, which form part of this specification, Figure 1, Sheet 1, is an end or top view of my sealing-press, adapted to raise retaining-projections on the threading ends of sheet-metal seal-shackles, the handles and dies being shown apart or open. Fig. 2 is a sideview of the same, partly in section, on the line 2 2, Fig. 1, showing the parts in full lines open and in dotted lines closed. Fig. 3 is an edge view of this press with parts open. Fig. 4 is another top view of the same with parts closed. Fig. 5 is a perspective view of the middle die of this press. Fig. 6 is a like view of the shearing block or knife of its shackle-cutter. Fig. 6^x represents a section through the shackle-cutter on the line 6^x, Fig. 2. Figs. 7 and 7^x are perspective views of pressed sheet-metal seals, illustrating the products of the dies of said press. Fig. 8, Sheet 2, is a sectional side view of my sealing-press specially adapted to apply lead-and-wire seals.

Fig. 9 is a face view of one of its dies. Fig. 10 is a top view of the pair of dies, and Fig. 11 is an elevation of a lead-and-wire seal pressed or stamped thereby. Fig. 12, Sheet 2, is a side view of the upper end of my sealing-press adapted to unite the ends of sheet-metal sealing-strips by eyelet-punching. Fig. 13 is a face view of the punching-die. Fig. 14 is a top view of the pair of dies, one of them in section; and Figs. 15 and 15^x are elevations of pressed sheet-metal sealing-strips, illustrating the products of this press.

Like letters of reference indicate corresponding parts in the several figures.

15 The terms "upper," "lower," "top," &c., are used with reference to the press as viewed in Figs. 2, 8, and 12.

My sealing-press, in each of its forms or adaptations, consists, principally, of a pair of 20 working-levers, L L', terminating at the respective ends of the press in handles h h and cams c c, and pivoted by parallel pins p p, or suitable trunnions, with a yoke frame or head, H, and a pair of pivoted or sliding dies or die-jaws, D D D² D² D³ D⁴, with a spring or springs, 25 s s² s², the spring or springs operating to separate or open the die-jaws, and, in combination with said cams, to hold the moving parts in the normal open position indicated by full lines in Figs. 2, 8, and 12, while the levers, through 30 said cams, operate powerfully and equally to force the respective die-jaws toward each other, or, in other words, to close the dies, as illustrated by dotted lines in Figs. 2 and 8. In 35 this combination of parts the full length of the press is utilized for leverage, and the power is applied in the most direct manner. The cams are, moreover, very simply constructed. A flat or nearly flat peripheral surface, against 40 which the back of the die-jaw rests when the dies are open, is connected by a simple curve with what I term the "shank" k of the lever, said flat or nearly flat peripheral surface of the cam being formed at the proper angle in relation 45 to the body of the lever to afford the required throw, and of proper length to locate the line of pressure at or about the middle or center of the dies, so as to render the action of the dies at their respective extremities as nearly as 50 possible uniform. In the examples the line of pressure is kept below the axes of the pivots, so that the die-jaws are never locked; but this is not considered essential. Each lever, with its handle and cam, is, moreover, or may be, a 55 counterpart of the other, and the same may be true of each die-jaw, while the division of pivot-strain renders practicable pivoting the levers by steel pins within a one-part yoke-frame, as shown, all of which tends to materially facilitate 60 and cheapen the manufacture of the press in either of its forms.

In the sealing-press illustrated by Figs. 1 to 7^x a two-faced middle die, D', is arranged between the die-jaws D D, and the faces of the 65 respective dies are provided with matching characters, intaglio in one face and cameo on the face opposite, being designed and adapted

to raise retaining-projections in the form of numbers or distinguishing-marks simultaneously on the respective threading ends of a seal-shackle, S, Fig. 7, both ends of which protrude through a contracted threading-hole in a tag or keeper, T, or to raise like retaining-projections on the single threading end of a seal-shackle, S², Fig. 7^x, one end of which is threaded through the other end thereof or through a tag of any shape integral therewith. The upper ends of the die-jaws D D and middle die, D', are constructed respectively with matching inclines and matching grooves and 80 prominences o o', to provide the pressed end or ends of the shackle with shoulders or offsets o², stiffened and thickened by means of raised ribs substantially parallel to the longitudinal edges of the shackles, to preclude the 85 withdrawal of said pressed end or ends through a contracted threading-hole. These stiffened and thickened offsets are so effective for this purpose, especially when used in pairs, as shown in Fig. 7, that the numbers or distinguishing-marks may be dispensed with or stamped without regard to prominence when used in connection therewith. The die-jaws are preferably provided with the intaglio faces, so as to offer no obstruction to the shackle 95 ends, which are deflected against said faces by the beveled upper end of the middle die, and a stop-projection or rest, r, is formed on the face of each die-jaw at its lower end, to arrest the shackle ends in proper position between 100 the dies. Said location of the intaglio faces serves also to facilitate repairs, as the intagliodie will not ordinarily require renewal, and the single cameo-die, being the middle die, is easily replaced. It is shown detached in Fig. 105 5. The die-jaws D D are pivoted at their lower ends between the depending cheeks of the head H by pins p² p², parallel to the pivots p p, and are connected beneath the same by a spring, s, common to both, the respective ends 110 of the spring being held in oblique kerfs in the backs of the respective die-jaws. The middle die, D', is held in place between the die-jaws by a removable pin, p', near its upper end. Its lower end is afforded lateral support by the 115 respective die-jaws. The employment of a single supporting-pin parallel to the pivots p p and midway between them, as shown, renders the middle die to some extent self-adjusting in relation to the die-jaws. To further facilitate 120 the removal of the middle die a screw or screws may be substituted for the pin p'.

A steel shearing block or knife, K, (shown detached in Fig. 6,) is held in a transverse dovetailed seat in one edge of the head H, as shown 125 in Figs. 2, 3, and 6^x, so as to coact with the sharp-cornered shank k of the right-hand lever L' as a shackle-cutter in removing seals or seals and tags of any kind. Instead of the two cutting-edges shown in Figs 6 and 6^x, the 130 knife K may have but one cutting-edge in some cases. The knife is supported, except against lateral movement, by the dovetailed form of the seat in which it is held, and is se-

cured against lateral displacement by the contiguous portion of the spring s occupying a longitudinal groove or notch, n , in the back of the knife, as shown in Fig. 2.

5 A single-acting press for stamping sheet-metal seal-shackles may be formed by simply omitting the middle die, D' , making one of the die-jaws D cameo, and suitably proportioning the parts. The novel construction of sealing-dies herein specified may also be embodied in sealing-presses of other forms.

By simply omitting the middle die, D' , and providing the sides or cheeks of the head H with suitable openings the sealing-press above 15 described, without changing the character of its die-jaws, is adapted for pressing or stamping the sealing-sleeves of my seals and tags patented December 21, 1880, and in this modified form it may be used, without further 20 change, to provide a shackle-wire with a securely-pressed lead seal of substantially the shape of said die D' , Fig. 5; but for pressing lead-and-wire seals I prefer to substitute a pair 25 of sliding die-jaws, D^2 D^2 , of the customary round form, with independent springs s^2 s^2 , and a head, H^2 , of modified construction adapted to accommodate these parts, as represented by Figs. 8 to 10.

Fig. 12 gives an external view of the head 30 H^2 , showing its illustrative construction more clearly. The top of said head H^2 is notched to receive a bushing, y , which is drilled before its insertion to form guides for the cylindrical die-jaws, and is held in place by screws, as shown 35 in Fig. 12.

The product, Fig. 11, may have a shackle-wire, S' , of any description, and the pressed seal-disk d' may be provided with numbers or distinguishing-marks, of any preferred description, by the respective dies.

The eyeleting seal-press illustrated by Figs. 12 to 15^x is formed by simply substituting a suitable punching-die, D^3 , and its counterpart D^4 for the dies D^2 D^2 in the press last described. 45 The products are the common eyeleted tin sealing-strips S^3 S^4 with two simultaneously-formed integral eyelets, or but one, as preferred, the same being formed by inserting the ends of a shackle together between the dies D^3 D^4 50 and punching them, and then reversing the shackle and repunching through the same hole or holes to clinch the spurs thrown up at the first operation. Dies for inserting commercial eyelets or soft-metal rivets may be substituted 55 in like manner, and do not require additional illustration or description. In either of the latter the shackle may be provided with numbers or distinguishing-marks at the eyeleting or riveting operation by reverse counterparts 60 of the desired characters in sharp cameo on one of the dies, as illustrated at x x^2 in Figs. 12 to 15^x; or the respective dies may be provided

with cameo and intaglio embossing-surfaces for the same purpose, or with suitable surfaces for stamping the said rivet-seals in customary 65 manner.

I am aware that a bolt-cutter has been constructed with a pair of hand-levers pivoted within a yoke frame or head, and constructed with cams at their pivot ends for operating a 70 pair of coacting knives by direct action. I therefore disclaim said combination, broadly considered.

Having thus described my said invention, I claim therein as new and desire to protect by 75 Letters Patent—

1. In a sealing-press, a pair of die-jaws supported within a yoke frame or head, with faces toward each other, in combination with a pair of working-levers pivoted within said head behind the respective die-jaws, and constructed with cams at their pivot ends adapted to actuate the respective die-jaws by equal, or nearly equal, direct pressure in a central plane, substantially as herein described, for simultaneously 85 pressing or stamping two seal-surfaces by independent die action.

2. The combination, in a sealing-press, of a pair of simultaneously-actuated die-jaws, having faces toward each other, and a two-faced 90 middle die between said die-jaws, for pressing or stamping the threaded end or ends of a sheet-metal seal-shackle, in the manner set forth.

3. The combination, in a sealing-press, of a pair of sealing-dies constructed with inclined 95 surfaces o o' , provided, respectively, with grooves and prominences adapted to provide the threaded end or ends of a sheet-metal seal-shackle with stiffened and thickened shoulders or offsets, substantially as herein described, to 100 preclude the withdrawal of the same through a contracted threading-hole.

4. In a sealing-press for pressing or stamping sheet-metal seal-shackles, the combination of a pair of intaglio die-jaws and a two-faced 105 cameo middle die, substantially as herein described, for the purposes set forth.

5. In a sealing-press for pressing or stamping sheet-metal seal-shackles, the combination, with a two-faced middle die, of a pair of die-jaws pivoted at their lower ends and connected beneath the said pivots by an opening-spring common to both, substantially as herein specified.

6. The shearing block or knife K , in combination with the yoke frame or head H , having a transverse dovetailed seat to receive said knife, and the die-spring s , engaging with the notched back of the knife, as specified, for the purpose set forth.

EDWARD J. BROOKS.
